Primary Examiner — Cathron Brooks*Assistant Examiner* — Sharon S Oum(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing my new design.

The broken line showings of the remainder of the display screen and the remainder of the graphical user interface illustrate portions of the display screen with graphical user interface and form no part of the claimed design.
